(57) **CLAIM**

The ornamental design for a cellular telephone, as shown and described.

DESCRIPTION

FIG. 1 is a front perspective view of a cellular telephone showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is a front elevational view thereof shown in an open state.

The stippled shading on the portion of the cell phone surrounding the clock face in FIGS. 1-3 and 5-7 represents color contrast.
